UNITED STATES PATENT OFFICE.

EDWARD W. MUELLER, OF BENSENVILLE, ILLINOIS.

FUNNEL.

1,085,626.

Specification of Letters Patent.

Patented Feb. 3, 1914.

Application filed May 24, 1911. Serial No. 629,113.

To all whom it may concern:

Be it known that I, EDWARD W. MUELLER, a citizen of the United States, and a resident of the city of Bensenville, county of DuPage, and State of Illinois, have invented certain new and useful Improvements in Funnels, of which the following is a specification.

My invention relates to improvements in funnels and has for its object the production of a funnel through the medium of which liquid may be introduced into a vessel with great expedition.

A further object is the production of a funnel as mentioned which will be adapted also to serve as an effectual strainer for the liquid passing therethrough.

Other objects will appear hereinafter.

With these objects in view my invention consists in a funnel characterized as above mentioned and in certain details of construction and arrangements of parts all as will be hereinafter described and claimed.

My invention will be best understood by reference to the accompanying drawings forming a part of this specification, and in which—

Figure 1 is a central longitudinal section of a funnel embodying my invention. Fig. 2 is a central longitudinal section taken at right angles to the section shown in Fig. 1, and Fig. 3 is a transverse section taken on line $x-x$ of Fig. 2.

The preferred form of my construction as illustrated in the drawings comprises a body 1 which is formed preferably of sheet metal, the same being of the usual tapering or conical form. Secured, preferably by soldering to the lower or contracted end of the body 1 is the usual tapering spout 2, and provided at the upper or mouth edge of the body 1 is a circular mouth piece 3 preferably secured thereto in the manner clearly illustrated. Arranged within the funnel are two diametrically disposed vent pipes 4, the same being rigidly secured, preferably by soldering, upon the inner surfaces of the body 1 and the spout 2; the lower ends of said vent pipes terminating adjacent the lower end of said spout and preferably slightly below the same. The upper ends of said vent pipes project exteriorly through the mouth piece 3 and terminate adjacent and slightly below the upper edge of the latter. By this arrangement both ends of the pipes 4 are free for entry and egress

of air and there is no possibility of the liquid poured into the funnel entering the upper end of said pipes.

With the provision of the vent pipes 4 it is apparent that, in operation, provision is made for the exhaust of air from the vessel in conjunction with which the funnel is used upon displacement of said air by the liquid introduced into the vessel through the funnel. This being so, the necessity of the air displaced bubbling up through the liquid entering through the spout is obviated and hence the flow of liquid through the nozzle rendered free and unimpeded, and so that the vessel may be filled with greater expedition. Also, by the provision of the pipes 4 positioned upon the inner surfaces of the body 1 and spout 2, the former will serve to prevent whirling of the liquid in the funnel, such whirling as is known being incidental to the draining of liquid through a restricted opening. This whirling as is known retards the downward flow of the liquid and when not prevented evidently results in the consumption of time required for the draining of the liquid through the funnel. With the provision of the vent pipes as shown, however, this whirling will be prevented and hence the retardation of the liquid caused by this whirling prevented.

Arranged in the body 1 at the opposite sides thereof and midway between the vent pipes 4 are downwardly convergent plates 5. Formed substantially centrally in the plates 5 are openings 6 behind which are arranged strainners 7 preferably of the wire mesh type which are secured in position preferably by soldering. With this provision the liquid introduced into the funnel in its passage from the body 1 to the spout will be required to pass through the strainer 7 before introduction into the vessel arranged below. The plates 5 are so arranged that at the apex or lower ends thereof will be formed a residue pocket 8 which will serve as a collector for foreign matter carried in the liquid, said matter, upon introduction of the liquid into the funnel settling in said pocket whence the same may be subsequently removed.

Arranged in the mouth piece 3 is a flexible strainer 9 formed preferably of chamois skin, said strainer 9 being held in traversing position in the mouth piece 3 by means of a spring ring 10 which is adapted to engage

a circumferential groove 11 formed in the inner surface of said mouth piece, the strainer 9 being clamped between said ring and the adjacent surface of said mouth piece as will be readily understood. The extremities 12 of the member 10 are bent inwardly, as shown in Fig. 3, so that the same may be readily engaged by the fingers to contract said retainer ring 10 in effecting arrangement thereof in the funnel or disengagement thereof therefrom.

With a construction then as set forth, it will be seen that, in use, the liquid introduced into the funnel will be first strained by the strainer 9. In passing through the body 1 the liquid will be subjected to a second straining by the strainers 7 and a portion of the solid foreign matter suspended in the liquid will be collected in the pocket 8 into which the same will settle. Thus the liquid passing through the funnel will be thoroughly clarified before being deposited into the vessel for consumption. Also, the construction is such that draining of the liquid through the funnel will be accomplished with great expedition, since whirling of the liquid therein will be prevented and exhaust of the air from the vessel accomplished without necessitating the passage of the exhausting air through inflowing liquid. If desired it is apparent that the strainer 9 may be readily removed and the device used without the same.

While I have illustrated and described the

preferred form of construction for carrying my invention into effect, this is capable of variation and modification without departing from the spirit of my invention. I, therefore, do not wish to be limited to the precise details of construction as set forth, but desire to avail myself of such variations and modifications as come within the scope of the appended claim.

Having described my invention what I claim as new and desire to secure by Letters Patent is:

A funnel comprising a body of inverted cone shape and a spout connected with the lower end thereof, inwardly and downwardly inclined walls in said body having their side and top edges secured thereto and their bottom edges secured together forming a pocket, each of said walls having its lower part disposed at a different degree of inclination to its upper part and a curved part joining said lower and upper parts; and strainer elements in said lower parts, each strainer element providing a separate communication from said body to said spout, substantially as described.

In testimony whereof I have signed my name to this specification in the presence of two subscribing witnesses.

EDWARD W. MUELLER.
